Primary Examiner — Raphael Barkai*(74) Attorney, Agent, or Firm* — Knobbe Martens Olson & Bear, LLP**(57) CLAIM**

The ornamental design for an eyeglass, as shown and described.

DESCRIPTION

FIG. 1 is a front perspective view of an eyeglass of the present invention;

FIG. 2 is a front elevational view of the eyeglass of FIG. 1;

FIG. 3 is a rear elevational view of the eyeglass of FIG. 1;

FIG. 4 is a left side elevational view of the eyeglass of FIG. 1, the right side elevational view being a mirror image thereof;

FIG. 5 is a top plan view of the eyeglass of FIG. 1; and,

FIG. 6 is a bottom plan view of the eyeglass of FIG. 1.

The areas of the eyeglass shown in broken lines form no part of the claimed design.
